UNITED STATES PATENT OFFICE.

JAMES L. TAYLOR, OF ISHPEMING, MICHIGAN.

PIPE-WRENCH.

SPECIFICATION forming part of Letters Patent No. 287,193, dated October 23, 1883.

Application filed June 20, 1883. (No model.)

To all whom it may concern:

Be it known that I, JAMES L. TAYLOR, of Ishpeming, in the county of Marquette and State of Michigan, have invented a new and 5 useful Improvement in Pipe-Wrenches, of which the following is a full, clear, and exact description.

The invention consists in a novel construction of said parts, or certain of them, and combinations of the same, including a reversible fixed head on the working end of the handle, having opposite concave serrated gripping-surfaces, a forked jaw of diverging construction toward the nut to which it is pivoted, 15 and an improved angular construction of said jaw at its gripping parts, substantially as hereinafter described, whereby increased strength is secured, a better grip is obtained, as also a more extended or varied gripping-surface, 20 and a cheap, simple, and durable wrench having an easy and extensive adjustment is produced.

Reference is to be had to the accompanying drawings, forming a part of this specification, 25 in which similar letters of reference indicate corresponding parts in all the figures.

Figure 1 represents a longitudinal view of a pipe-wrench embodying my invention; Fig. 2, a partly-broken similar view of the same 30 in a plane at right angles to Fig. 1, and Fig. 3 an edge view of a modified construction of the swinging jaw.

Referring, in the first instance, to Figs. 1 and 2 of the drawings, A is the shank or metal 35 portion of the handle, fitted with a wooden hand holding part or sleeve, A'. The protruding metal shank portion A of the handle is of circular form in its transverse section, and of increased diameter, where a screw-thread, b, is formed upon it, to provide for the 40 nut B being passed on it from the back end of the shank, and to give the handle increased strength.

The outer or working end of the handle or 45 shank portion A is formed or fitted with a fixed head, C, that is or may be of square form at its base, where it joins the screw-threaded portion b, but which is of reduced tapering construction outward therefrom on two of its 50 opposite sides, c c, which are serrated. This

head C constitutes what may be termed the "fixed jaw" of the wrench, and by being serrated on opposite sides it is made reversible each half-turn of the handle; and, if desired, its opposite serrated sides may be at different angles to suit different kinds of work. This reversible provision of the head or fixed jaw— 55 that is, jaw in solid connection with the handle—gives a more varied gripping-surface, and consequently reduces wear. Furthermore, 60 the serrated surfaces c c of said head are concave in direction of the length of the head, thereby giving a better hold or grip than if the same were convex. The sloping configuration of the surfaces c c should be such as to 65 adapt said surfaces to the largest pipe the wrench is designed for.

The screw-threaded portion b of the handle should be twice the length, or thereabout, of the nut B, which fits thereon, or otherwise 70 sufficiently long to allow of the head C moving outward to close with the swinging jaw D.

The nut B, which is a long one, has two of its opposite sides flattened, to form bearings 75 for the forked ends d d of the swinging jaw 75 D, pivoted at e to the nut. Said forked end portions, d d, are made diverging toward the nut, thus giving an increased width for the swinging jaw at its bearing, and allowing of a stouter nut and thicker or stronger handle 80 being used. The forked portions d d should be made sufficiently diverging to provide for a shank A of sufficient size being used to resist ordinary strain. The remaining portion of the jaw D, which narrows toward its outer 85 end, should be of corresponding width, or thereabout, with the head C. This portion, as illustrated in Figs. 1 and 2, is of hook form, and is serrated internally on its concave face, which may be of a quarter of a circle (more 90 or less) in length, to give a firm and steady grip on the pipe P as the wrench is worked in direction of the arrow x. When worked in a reverse direction, it releases its grip, as in the case of other pipe-wrenches hereinbefore 95 referred to.

Instead of the swinging jaw D being of curved hook shape at its outer or gripping end, it may be of angular V form, as represented in Fig. 3, so as to present two serrated angular grip- 100

ping-surfaces, slightly curved where they meet each other and join the remaining portion of the jaw. When the jaw D is thus constructed, the wrench will have three bearing-surfaces 5 on the pipe to which it may be applied.

The adjustment of the wrench is effected by turning its handle or by turning the nut with its attached jaw on the handle.

Having thus described my invention, I claim 10 as new and desire to secure by Letters Patent—

1. In a wrench, the fast head or jaw C, having the opposite serrated sides, *c c*, in combination with a concave swinging jaw, D, forked

and provided with duplicate inner serrated sides, as and for the purpose specified. 15

2. The combination, with the shank portion A of the handle, having a screw-thread, *b*, on it, of the fast head or jaw C, having opposite concave serrated sides, *c c*, converging toward one another in an outward direction, the nut 20 B, and the forked jaw pivoted to said nut, essentially as shown and described.

JAMES L. TAYLOR.
